DISTANCE MEASURING INSTRUMENT

Wallace D. Evans, Jr., Los Angeles, Calif., assignor to
Rolatape Corporation, Santa Monica, Calif.

Filed Jan. 22, 1973, Ser. No. 325,324

Term of patent 14 years

Int. Cl. D10—04

U.S. Cl. D52—6 R

FIG. 1 is a left front perspective view of a distance measuring instrument showing my new design;

FIG. 2 is a top plan view thereof, the handle having been omitted for ease of illustration;

FIG. 3 is a front elevational view thereof as taken from line 3—3 of FIG. 2;

FIG. 4 is a bottom plan view thereof as taken from line 4—4 of FIG. 3;

FIG. 5 is a rear elevational view thereof as taken from line 5—5 of FIG. 2;

FIG. 6 is a right side elevational view thereof as taken from line 6—6 of FIG. 5.

I claim:

The ornamental design for a distance measuring instrument, substantially as shown and described.
